TRANSMON CONTROLLER

Filed May 23, 1938

FIG. 1

INVENTOR.

CHARLES W. WARD

Victor J. Evans & Co.
ATTORNEY.

UNITED STATES PATENT OFFICE

2,177,446

TRANSOM CONTROLLER

Charles W. Ward, Los Angeles, Calif.

Application May 23, 1938, Serial No. 209,585

1 Claim. (Cl. 268—113)

This invention relates to transoms and more particularly to improvements in transom actuating and locking means.

An object of the invention is to provide a simple, practical and inexpensive device of the character described.

Another object is to provide a transom actuating and locking means which is substantially concealed within the framework of the door.

Another object is to provide a transom actuating and locking means which may be attached to the ordinary transom without changing its construction.

Another object is to provide a transom actuating and locking means which can be operated with one hand.

Other objects and advantages will appear and be brought out more fully in the following specification, reference being had to the accompanying drawing wherein

Fig. 1 is a side view of a door jamb and transom illustrating my invention and

Fig. 2 is a fragmentary front view of the same.

Referring more particularly to the drawing, I show a door jamb 5, a door member 6, a transom 7 having a hinge 8 secured to a lower frame member 9 of the transom and door member 6. A bracket 10 is suitably secured to transom 7 near the upper portion thereof and has an arm 11 extending over door jamb 5. Bracket 12 is suitably affixed to door jamb 5 behind arm 11 and extends through an aperture 13 in door jamb 5 and supports a pulley 14 at the interior end thereof. A cord 15 passes over pulley 14 and has its upper end secured to arm 11. The lower end of the cord is secured to a plate 16 which is slideably positioned between the sides of a clevice 17, a spring 18 being positioned between plate 16 and the top of clevice 17. Clevice 17 is pivoted at 19 to an arm 20 of an operating member 21 having a suitable grip portion 22, the arm 20 being adapted to extend through a slot 23 in a plate 24 suitably affixed to the outside of door

jamb 5 in which a suitable elongated aperture 25 is formed to permit the reception of arm 20 and vertical movement thereof. Boss 26 is secured to or formed integrally with arm 20 on each side thereof and has an arcuate edge 27 adapted to form a lock in cooperation with a pin 28 which extends through arm 20, a suitable bearing plate 29 being provided between pin 28 and plate 24 if desired. Door member 6 has a recess 30 in which is located a tubular member 31 having a compression spring 32 therein, the upper end of which bears against a plate 33 suitably recessed in transom frame member 9.

From the above construction it will be apparent that operating member 21 may be raised and inclined a small amount to release the locking action of bosses 26 and pin 28 and that the transom 7 can be readily opened or closed by appropriate manipulation of the operator 21, the spring 32 serving to open the transom 7 a sufficient amount to enable the weight of the transom to cause further opening movement. The operator 21 can be manipulated by one hand and locked in any position with the transom opened any amount.

Having described my invention, what I claim is:

An operator and lock for a transom or the like having a lower member hinged to a door frame, a bracket on the upper portion of the transom, a member within the door frame, a cable within said frame and terminally connected to said bracket and said member, said frame having an aperture, a plate on said frame over said aperture and having a slot, a lever arm extending through said slot and aperture and pivotally connected to said member, and a fulcrum and an arcuate boss on said arm disposed on opposite sides of said plate whereby said arm may be locked to said plate when tension is applied to said cable, said arm adapted to be released by pivotal action with respect to said fulcrum.

CHARLES W. WARD.
